PULL TOY

John Kintas, Wichita, Kans.

Application July 27, 1950, Serial No. 11,436

Term of patent 3½ years

(Cl. D34—15)

To all whom it may concern:

Be it known that I, John Kintas, a citizen of the United States, residing at Wichita, State of Kansas, have invented a new, original, and ornamental Design for a Pull Toy, of which the following is a specification, reference being had to the accompanying drawing, forming a part hereof:

Fig. 1 is a left side elevation of a pull toy showing my new design;

Fig. 2 is a front elevation of the same; and

Fig. 3 is a right side elevation of the same.

I claim:

The ornamental design for a pull toy, as shown.

JOHN KINTAS.
